UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

PLATEN-SHIFT.

1,121,036.

Specification of Letters Patent. Patented Dec. 15, 1914.

Application filed September 15, 1910. Serial No. 582,216.

To all whom it may concern:

Be it known that I, OTTO PETERMANN, a citizen of the Republic of Switzerland, and a resident of Groton, county of Tompkins, and State of New York, have invented certain new and useful Improvements in Platen-Shifts, of which the following is a full, clear, and exact description.

This invention relates more particularly to the platen shifts of visible, foldable type-writing machines.

The primary object of the invention is to provide simple and efficient means whereby the platen may be shifted to different positions by means located at one side of the machine, and which means is so constructed that the platen and carriage may be moved into compact relation to another part of the machine for transportation or for other purposes.

A further object of the invention is to provide simple and efficient means which will positively hold and limit the movement of the platen in its different shiftable positions, and to provide means for locking the platen in such different positions.

With these and other objects in view, the invention will be hereinafter more particularly described with reference to the accompanying drawings, which form a part of this specification, and will then be pointed out in the claims at the end of the description.

In the drawings Figure 1 is a longitudinal section of a part of one form of machine embodying my invention. Fig. 2 is a fragmentary sectional plan view, taken on the line II—II of Fig. 1; and Fig. 3 is a vertically transverse section taken on the line III—III of Fig. 1, the upper part of the machine being removed.

The frame 10 may be of any suitable construction and may have the usual keys forming a keyboard which are operatively connected to the type-bars to adapt the same to be forced to printing position against the platen 11. The platen is mounted upon a carriage 12 and said carriage is held to move transversely of the machine along the support 13, the latter being pivoted at 14 to permit the carriage and platen to be shifted into overhanging relation to the keyboard, all of which may be of the usual or of any preferred construction.

The platen and its support is adapted to

move vertically to different positions for the different characters on the type heads, and said support at opposite sides of the machine is provided with a vertically-extending bar 15 which is held to slide vertically in the post 16 located at the corner of the machine frame. At one side of the machine and adjacent to the frame are the shift levers 17 and 18. The shift lever 17 is pivotally held either loosely or otherwise to a transversely-extending rod 19 and the rear end of said lever is connected to a rod 20 which extends transversely of the machine and serves to join the two bars 15 to adapt the same to be moved in unison. The outer end of the lever 17 is provided with a key or finger portion 21 to adapt the shift lever 17 to be moved or forced downward in the usual manner. In the form of machine shown, the type-heads are adapted to contain three sets of characters, one for the upper case characters, a second for the lower case characters, and the third for figures and the like. In Fig. 1 the platen and parts are shown in the normal position and for the lower case characters, and the lever 17 is intended to shift the platen vertically in position for the upper case characters, while the shift lever 18 gives another throw to the platen and is intended for the figures or other characters. This shift lever 18 has a hooked part, as 22, to fit about a part of the transverse rod 19 which serves as a pivot for said lever, and this lever has a finger part or key 23 at its outer end and is held to the lever 17 so as to have a relative limited movement with respect thereto. As shown, the lever 17 is provided with a slot 24 located adjacent to the pivot rod 19; through which passes a screw or pin 25 one end of which is held to the lever 18 so that the lever 17 by means of the slot-and-screw connection may have a downward movement for a certain distance without operating the shift lever 18.

The shift lever 18 is provided with a cam portion or end 26 which is adapted to engage a projection or part 27 extending inward and formed as a part of an arm 28. This arm 28 is pivoted at 29 to the inner side of the machine frame and is connected by a spring 30 to the lever 18, said spring being fastened at one end to the said arm and its other end being fastened to a projection 31 on said lever 18. The lever 18

100

105

110

has a lip or projecting part 32, and this part is adapted to fit over the projection 27 of the arm and the tendency of the spring 30 is to force the projecting part 27 into contact with the end 26 of the lever 18. At 5 the upper end of the arm 28 are arranged two elements 33 and 34. As shown, these elements are in the form of screws and said screws pass through an inwardly-projecting part 34^a at the upper end of the arm and through lugs 35 and 36, respectively, which lugs may be forced from the body portion of the arm 28. The screws 33 and 34 are adjustable and are of relatively different lengths 10 to permit different vertical adjustments to be given the platen 11, and each of said screws is adapted to engage the inturned end 37 of the bracket or plate 38 projecting downward from the platen support, the said 15 bracket being of any suitable form and arranged in any desired way to adapt the same to engage the screws according to the position of the arm 28.

As will be seen when the parts are in the 20 position shown and the shift lever 17 operated, the bars 15 connected to the platen support may be moved to their maximum throw and until the inturned end 37 of the bracket 38 engages the screw or element 34 which will limit the upward movement of 25 the platen and support. When the lever 18 is depressed, this lever will throw the arm 28 inward on its pivot until the screw 33 is in the path of movement of the inturned 30 end 37 of the bracket 38 and at the same time that the lever is moved downward, it will force the bars 15 upward to shift the platen and its support until the inturned end 37 engages the lower end of the screw 35 33, the position of the platen being determined by the adjustment of the said screws. By placing the two shift levers on the same side of the machine a number of the connecting parts may be dispensed with and a 40 very simple construction provided and which also serves as a more convenient means for shifting the platen.

To lock the shift levers independently of each other to hold the platen in either of its 45 shifted positions so that the same character of type may be employed without constantly using the shift key, I provide each shift lever with a hook or lip 39 forming a recess 40 under each lever and these recesses are 50 adapted to have the end 41 of the lever 42 enter the same and prevent their upward movement until said lever is released. The lever 42 is pivoted at 43 to the inner surface of one side of the machine frame and 55 has two arms 44 each provided with an extended part 45. These arms 44 form a bifurcated portion of the lever and the outwardly-extending parts 45 serve to engage the upper edge of the side of the frame to 60 limit the movement of the lever 42 so that

the said lever in one position is disengaged and out of the path of movement of the shift levers while in its other position the end 41 will enter the recess 40 of one of the shift levers according to which one has been 70 forced downward, the said lever being restored to its normal position by the weight of the carriage or platen or by one or more springs, if desired. A projection or lip 46 may be arranged between the arms 44 and 75 this lip is adapted to enter a recess or slotted portion 47 of the lever 17 to prevent the same from being shifted to elevate the platen.

From the foregoing, it will be seen that 80 simple and efficient means is provided whereby the platen may be shifted vertically to different adjustments; and that simple and efficient means is provided for locking the shift levers and consequently 85 the platen in their adjusted positions.

Having thus described my invention, I claim as new and desire to secure by Letters Patent:—

1. In a typewriting machine, the combination with a vertically movable support, of a platen mounted on said support, two shift levers arranged in close relation to each other on the same side of the machine for moving the support and platen to different vertical positions, a pendent bracket movable with the support, and a single movable element adapted to engage the bracket in different positions thereof to limit the shifting movements of the platen. 90

2. In a typewriting machine, the combination with a support, of a platen mounted on the support, two shift levers having relatively different movements for adjusting the platen and support to different heights, the 105 said levers being arranged in close relation and pivotally held adjacent to one side of the frame, a bracket carried by the adjustable support, a pivoted arm adapted to engage the bracket when moved by one of the 110 shift levers to limit the upward movement of the arm, and means movable with the other shift lever adapted to force the arm to permit another movement of the bracket and thereby the platen and support. 115

3. In a typewriting machine, the combination with a support, of a platen mounted on the support, two shift levers having relatively different movements for adjusting the platen and support to different degrees, the said levers being arranged in close relation and pivotally held adjacent to one side of the frame, a pivoted stop arm adapted to engage a part movable with the support in its normal position, and means 120 whereby one of the shift levers only is adapted to force the arm to limit the shift movement of the platen and support and to a different degree than when in its normal position. 125

4. In a typewriting machine, the combination with a support, of a platen mounted on the support, two shift levers having relatively different movements for adjusting the platen and support to different degrees, the said levers being arranged in close relation and pivotally held adjacent to one side of the frame, and a vertically arranged and pivoted arm adapted to limit the shifting movements of the platen according to the position of said arm.

5. In a typewriting machine, the combination with a support, of a platen mounted on the support, two shift levers arranged in close relation and pivotally held adjacent to one side of the machine frame for adjusting the platen and support, a stop carried by the adjustable support and fixed thereto, a movable arm adapted to engage the stop and to limit the movement of the same, and means movable with one of the shift levers, adapted to force the arm to permit a less movement of the stop and thereby the platen and support.

25 6. In a typewriting machine, the combination with a support, of a platen mounted on the support, two shift levers arranged in close relation and pivotally held to have a relative movement with respect to each other adjacent to one side of the machine frame for adjusting the platen and support, a stop carried by the adjustable support and fixed thereto, a movable arm adapted to engage the stop and to limit the movement of the same, and a projection on the arm engaged by one of the shift levers to force the arm to permit a less movement of the stop and thereby the platen and support.

7. In a typewriting machine, the combination with a support, of a platen mounted on the support, two shift levers for adjusting the platen and so connected as to have independent movements to adjust the support and platen to different positions, 40 slidingly held bars connected to the support, a transverse rod connecting the bars and held to one end of one of the shift levers, a pivoted arm provided with two elements of relatively different distances from the pivot, said arm having a projection adapted to be engaged by the second lever, a spring normally forcing the arm toward one of the levers to cause the projecting part to be engaged by the end of said second lever, and a bracket carried by the support and adapted to engage the elements of the arm to limit the movement of said bracket and support according to which shift lever is depressed.

55 8. In a typewriting machine, the combination with a support, of a platen mounted on the support, two shift levers for adjusting the platen and so connected as to have independent movements to adjust the support and platen to different vertical po-

sitions, slidingly held bars connected to the support, a transverse rod connecting the bars and held to one end of one of the shift levers, a pivoted arm provided with two elements of relatively different distances from the pivot, said arm having a projection adapted to be engaged by the second lever, and a bracket carried by the support and adapted to engage the elements of the arm to limit the movement of said bracket and support according to which shift lever is depressed.

9. In a typewriting machine, the combination with a support, of a platen mounted on the support, two shift levers for adjusting the platen and so connected as to have independent movements to adjust the support and platen to different positions, slidingly held bars connected to the support, a transverse rod connecting the bars and held to one end of one of the shift levers, a pivoted arm provided with two adjustable elements of relatively different distances from the pivot, said arm having a projection adapted to be engaged by the second lever, a spring normally forcing the arm toward one of the levers to cause the projecting part to be engaged by the end of the said second lever, and means carried by the support and adapted to engage the elements of the arm to limit the movement of said bracket and support according to which shift lever is depressed.

10. In a typewriting machine, the combination with a support, of a platen mounted on the support, two shift levers for adjusting the platen and so connected as to have independent movements to adjust the support and platen to different positions, slidingly held bars connected to the support, a transverse rod connecting the bars and held to one end of one of the shift levers, a movable arm having a projection adapted to be engaged by the second lever, and a bracket carried by the support and adapted to engage the arm to limit the movement of said bracket and support according to which shift lever is depressed.

11. In a typewriting machine, the combination with a movable support, of a platen mounted on said support, two shift levers arranged in close relation to each other on the same side of the machine for moving the support and platen to different positions, a pendent bracket movable with the support, and a single movable element having different positions and adapted to engage the bracket to limit the shifting movement of the platen.

12. In a typewriting machine, the combination with a movable support, of a platen mounted on said support, two relatively movable levers located adjacent to each other and so connected as to have independent movements, and a vertically arranged single element having different posi-

tions and actuated by one lever only whereby the levers may shift the platen different distances.

13. In a typewriting machine, the combination with a vertically movable support, of a platen mounted on said support, two relatively movable levers located adjacent to each other and having a pin-and-slot connection so as to have independent movements, and vertically arranged single pivoted means whereby the levers may shift the platen to different distances.

14. The combination with a vertically adjustable support and means for moving the same, of a platen mounted on said support, an arm pivoted to a part of the machine and provided with a projecting portion having two adjusting screws therein in relatively different positions and adapted to serve as stops for the support, and two relatively movable shift levers located adjacent to each other and adapted to impart relatively different vertical movements to the support.

15. The combination with a vertically adjustable support and means for moving the same, of a platen mounted on said support, an arm pivoted to a part of the machine and provided with two adjusting screws therein in relatively different positions and adapted to serve as stops for the support, and two relatively movable shift levers located adjacent to the frame and connected together and adapted to impart different movements to the support.

16. The combination with a support, of a platen mounted on said support, a pivoted arm having means adapted to engage a part of the support to limit its movement, a shift lever connected to the support for elevating the same, a second lever located adjacent to the first-mentioned lever and connected thereto and having a cam end adapted to engage a part of the arm to shift its position, and a spring connecting the arm and said second lever tending normally to force the arm and said lever together.

17. The combination with a support, of a platen mounted on said support, a pivoted arm having means adapted to engage a part of the support to limit its movement, a shift lever connected to the support for elevating the same, and a second lever located adjacent to the first-mentioned lever and connected thereto and having a cam end adapted to engage a part of the arm to shift its position.

18. The combination with a support, of a platen mounted on said support, a pivoted arm having means adapted to engage a part of the support to limit its movement, a

shift lever connected to the support for shifting the same, and a second lever located adjacent to the first-mentioned lever and connected thereto and adapted to engage a part of the arm to shift its position.

19. The combination with a vertically movable support, of a platen mounted on said support, two shift levers operatively connected to the support, means whereby the support may be limited in its vertical adjustments, said levers being provided with a lip and a recessed portion adjacent to said lip, and a pivoted lever having an end adapted to engage either of the shift levers and provided with a bifurcated handle portion, the arms of which are provided with an overhanging portion adapted to engage a part of the machine frame to limit the movement thereof.

20. The combination with a vertically movable support, of a platen mounted on said support, two shift levers operatively connected to the support, means whereby the support may be limited in its adjustments, said levers being provided with a lip and a recessed portion adjacent to said lip, and a pivoted lever having means adapted to engage the recess of either of the shift levers and provided with a bifurcated handle portion, the arms of which are provided with an overhanging portion adapted to engage a part of the machine frame to limit the movement thereof.

21. The combination with a vertically movable support, of a platen mounted on said support, a frame, two shift levers operatively connected to the support, means whereby the support may be limited in its adjustments, and a single pivoted lever entirely independent of the shifting means and having a movement limited in two directions by its engagement with the frame and provided with means to engage the shift levers one at a time and lock said levers against movement.

22. The combination with a vertically movable support, of a platen mounted on said support, two shift levers, operatively connected to the support, means whereby the support may be limited in its adjustments, said levers being provided with recessed portions, and a pivoted lever having a projecting lip to engage one of the levers and an end adapted to engage either of the shift levers.

This specification signed and witnessed this 12th day of September A. D. 1910.
OTTO PETERMANN.
